UNITED STATES PATENT OFFICE.

JESSE PERSLEY, OF TOPEKA, KANSAS.

TRACTOR.

1,164,208.

Specification of Letters Patent. Patented Dec. 14, 1915.

Application filed April 26, 1915. Serial No. 24,062.

To all whom it may concern:

Be it known that I, JESSE PERSLEY, a citizen of the United States, residing at Topeka, in the county of Shawnee and State of Kansas, have invented certain new and useful Improvements in Tractors, of which the following is a specification, reference being had to the accompanying drawings.

This invention relates to certain improvements in tractors and has relation more particularly to a device of this general character especially designed and adapted for use in connection with binders or other similar agricultural machines; and it is an object 15 of the invention to provide a device of this general character having novel and improved means whereby it may be operated with facility and may be applied in operative position with convenience.

20 The invention consists in the details of construction and in the combination and arrangement of the several parts of my improved tractor whereby certain important advantages are attained and the device is 25 rendered simpler, less expensive and otherwise more convenient and advantageous for use, all as will be hereinafter more fully set forth.

The novel features of the invention will 30 be carefully defined in the appended claims.

In order that my invention may be the better understood, I will now proceed to describe the same with reference to the accompanying drawings, wherein—

35 Figure 1 is a view in side elevation of a tractor constructed in accordance with an embodiment of my invention, a coacting binder being diagrammatically indicated by dotted lines, with a portion in section; Fig. 40 2 is a view in top plan of my improved tractor as herein set forth with the base portion of the tractor indicated in fragment and in full lines; Fig. 3 is a view in end elevation of my improved tractor with the coacting pointer indicated partly in full lines and partly in dotted lines; and Fig. 4 is an enlarged fragmentary sectional view illustrating the reversing mechanism herein embodied.

50 As disclosed in the accompanying drawings, 1—1 denote parallel side bars of predetermined dimensions and having their opposite extremities occupying different horizontal planes with the forward portion of 55 said bars occupying the lower plane. The

opposite extremities of the bars 1—1 are tied or connected by the cross bars 2 and projecting upwardly from the forward cross bar 1 at substantially its longitudinal center is the arcuate member or neck 3 and having 60 secured to its upper or free extremity the head 4 in which is rotatably supported the steering fork 5 in which is mounted in a conventional manner the wheel 6.

Any suitable means may be employed for 65 imparting the requisite steering movement to the fork 5 but as herein disclosed said fork is provided with the laterally disposed arm 7 operatively engaged with the rod 8 provided with a rack 9 mounted in such a 70 manner whereby it is caused to mesh with the pinion 10 fixed to the steering post 11.

As the exact manner whereby the forward wheel 6 is steered forms in its details no particular part of my invention, a detailed 75 disclosure is believed to be unnecessary as such changes as may be demanded by the necessities of practice may be readily made.

The rear or elevated portions of the side bars 1 are provided with the depending 80 bearings 12 in which are rotatably supported the extremities of the shaft 14 disposed transversely of the frame and to which is fixed the traction wheel 15, said wheel being positioned between the bars 1 85 and substantially in alignment with the forward head 4, hereinbefore referred to.

The intermediate portions of the forward or lower extremities of the bars 1 are provided with the spring supporting members 90 16 with which are operatively engaged the beams 17 to which the frame of a binder or the like is adapted to be secured and as is particularly indicated at 18 in Figs. 1 and 2. It is to be understood that the binder straddles the tractor in a manner as is indicated in Fig. 3 and that my improved tractor is adapted to take the place of the traction wheels generally employed in agricultural implements of this general character.

100 Operatively supported by the vertical portions 19 connecting the adjacent extremities of the end portions of the bars 1 are the substantially vertically aligned shafts 20 and 21, the shaft 20 being operatively engaged, as indicated at 22, with the shaft 14 at opposite sides of the traction wheel 15, while the shaft 21 is similarly connected as at 23, with the shaft 14. The shaft 21 constitutes the 105 transmission shaft of my improved tractor 110

and is operatively connected with the motor M through the medium of the driving shaft 24.

As is particularly illustrated in detail Fig. 4, the driving shaft 24 extends within the casing 25 and has its inner extremity provided with the gear 26 in mesh with the oppositely arranged gears 27 loosely mounted upon the transmission shaft 21. The 10 gears 27 are provided with the opposed clutch faces 28 with which coacts the clutch member 29 slidably mounted upon the shaft 21 but keyed thereto so as to rotate therewith. It is thought to be clearly apparent to those 15 skilled in the art to which my invention pertains that upon requisite engagement of the clutch member 29 with either of the gears 27, the transmission shaft 21 may be caused to rotate in the manner desired. In order 20 that the requisite endwise movement may be imparted to the clutch member 29, I have the same operatively engaged in a conventional manner by the lever 30.

The forward or lower portions of the bars 25 1 adjacent their inner extremities are provided with the transversely disposed shaft 31 operatively engaged, as at 32, with the shaft 20, and said shaft 31 is adapted to be connected in any conventional way and as 30 indicated at 33, with a movable part of the binder whereby it will be perceived that in addition to serving as a means for transporting the binder, my improved tractor also serves as a source of power for positively 35 operating the parts thereof.

From the foregoing description, it is thought to be obvious that a tractor constructed in accordance with my invention is of an extremely simple and comparatively 40 inexpensive nature and is particularly well adapted for use by reason of the convenience and facility with which it may be assembled, and it will also be obvious that my invention is susceptible of some change and 45 modification without material departure from the scope of the appended claims and for this reason I do not wish to be under-

stood as limiting myself to the precise arrangement and formation of the several parts herein shown in carrying out my invention in practice. 50

I claim:

1. In combination with a binder, a tractor therefor comprising a frame, a steering wheel supported by one extremity of the 55 frame, a traction wheel rotatably supported by the opposite extremity of the frame, a motor carried by the frame adjacent the traction wheel and operatively engaged therewith, beams yieldably supported by 60 the frame between the motor and the steering wheel to which the binder is secured.

2. In combination with a binder, a tractor therefor comprising a frame, a steering wheel supported by one extremity of the 65 frame, a traction wheel rotatably supported by the opposite extremity of the frame, a motor carried by the frame adjacent the traction wheel and operatively engaged therewith, beams yieldably supported by 70 the frame between the motor and the steering wheel to which the binder is secured, and an operative connection between the motor and a movable part of the binder.

3. In combination with a binder, a tractor 75 therefor comprising a frame, a steering wheel supported by one extremity of the frame, a traction wheel rotatably supported by the opposite extremity of the frame, a motor carried by the frame adjacent the 80 traction wheel and operatively engaged therewith, beams yieldably supported by the frame between the motor and the steering wheel to which the binder is secured, the portion of the frame with which the beams 85 coact occupying a horizontal plane below the plane of the rear portion of the frame.

In testimony whereof I hereunto affix my signature in the presence of two witnesses.

JESSE PERSLEY.

Witnesses:

PHILIP C. WILSON,
M. F. JOHNSMEYER.
